UNITED STATES PATENT OFFICE

2,482,539

AIR-OPERATED PRESS

Uri D. Foster, Hartford, Conn., assignor to The Arrow-Hart & Hegeman Electric Co., Hartford, Conn., a corporation of Connecticut

Application November 4, 1943, Serial No. 508,967

7 Claims. (Cl. 113—45)

1

This invention relates to air-operated presses in which the air is used to supply the force for driving one die into engagement with another. Presses of this type as heretofore used have not been economical in their use of compressed air. This has increased, unnecessarily, the cost of operating.

It is an object of my invention to provide an improved form of air-operated press embodying the features of safety to the operator, economy in operation and simplicity in structure.

It is another object of the invention to provide a press of the foregoing type with actuating mechanism requiring the use of both hands of the operator and embodying structure for opening the inlet valve with a sudden or snap motion.

Another object of the invention is to provide for utilization of the exhausted air to remove the stamped part from the dies after completion of the stamping operation.

Another object is to provide a novel combination of actuating means to insure the closing of the exhaust valve upon the actuation of either one or both of the operating handles and to prevent actuation of the inlet valve until both handles are operated. A related object is to prevent opening of the exhaust valve until the inlet valve is closed by the operator removing both hands from the operating handles.

Other objects and advantages of the invention will become apparent as it is described in connection with the accompanying drawings.

In the drawings—

Fig. 1 is a side elevation view of a press embodying the invention;

Fig. 2 is a vertical section view of the press of Fig. 1, taken along line 2—2 of Fig. 3;

Fig. 3 is a front elevation view of the press of Fig. 1;

Fig. 4 is a section view taken along line 4—4 of Fig. 2;

Fig. 5 is a plan view of the press of Fig. 1;

Fig. 6 is a horizontal section view taken along line 6—6 of Fig. 1;

Fig. 7 is an elevational detail view of one side of the valves operating mechanism, with the mechanism in a position intermediate its position in Figs. 1 and 8;

Fig. 8 is a view similar to Fig. 7, with the illustrated portion of the valves operating mechanism in its fully depressed condition; and

Fig. 9 is a detail section view taken on line 9—9 of Fig. 2.

Referring to the drawings, the invention is mounted upon a metal casting or frame comprising

15 ing a platform or base 12, from one end of which vertically rises a supporting column 14. From the top of the column 14 a horizontally-extending arm 16 overhangs the base 12. From the overhanging end of the arm 16 rises a vertical extension 18, which is vertically bored to receive a cylindrical piston 20. To keep the piston from rotating, a flat portion is formed on the piston, against which lies the flat face of a key member 24 which is held fixedly in a horizontal slot in the front face of extension 18 by a plate 26 bolted to said face.

20 Closing the top of the bore 19 is a cap member 28 which rests upon the top of the extension 18. 15 A guide boss 29 is formed on the upper surface of the cap 28 and it and the cap are bored to receive a piston rod 30 whose lower end threads into an internally threaded bore in the top of the piston 20. To raise and to normally bias the piston and 20 piston rod upwardly, a coiled compression spring 32 has its lower end seated upon the top of the 25 cap member 28, while its upper end presses against the under side of a flange 34 on a collar 36 that is slidably mounted upon the piston rod 30. To locate the collar 36 and thereby to limit 30 and adjust the amount of downward motion of the piston 30, an adjustment nut 38 is threaded upon the top threaded end of the piston rod; and the position of adjustment is maintained by a lock nut 40.

35 Secured to the lower end of the piston 20 is a die supporting rod 50 whose upper end is received within a bore 52 in the lower end of the piston 20 and is secured there by a diametric pin 53. 40 Upon the lower end of the die supporting rod 52 is a die member 54. To keep this die member from rotating on the supporting rod 50 a flat-bottomed notch 58 is formed in one side of the rod and a pin 56 passes horizontally through the die 54 in such position as to engage the flat bottom of said notch. Thus, the die is permitted limited movement relatively to the supporting rod 50 within the length of the notch 58. In order to hold the die normally in its lower position on the supporting rod 50, a compression spring is coiled about the shank of the supporting rod, with its upper end pressing against the bottom of the piston 20 and its lower end pressing upon the top of the die 54.

45 50 To enable compressed air to enter around the top of the piston 20, a circumferential cut 21 is made there, leaving a space to communicate with a passage or bore 70 vertically directed downwardly to communicate with a horizontal bore 72 extending through the overhanging arm 16 of

the press frame. The outer end of the bore or passage 72 may be closed by a screw, or in any other convenient fashion.

The inflow of air to the passage 72 is controlled by a manually operated valve which is provided with mechanism to cause the valve to open with a sudden or snap action. This valve comprises a hollow cylindrical plug 80 screwed into a vertical bore 82 through the top of the frame arm 16. The member 80 is centrally bored along its axis to receive the stem 84 of a valve member which has on its lower end an enlarged beveled head 86 adapted to engage and seat upon a similarly tapered seat 88 at the bottom end of the plug. Between the valve head 86 and the valve stem 84 is a reduced neck portion 90 permitting the entrance of air around such neck when the valve head 86 is moved from its seat 88. A plurality of radial passages are drilled through that portion of plug 80 which is within the passage 72 and adjacent the neck 90 of the valve stem to permit passage of air around the neck and head of the valve member when it is unseated.

Provision for entrance of compressed air beneath the head of the valve 86 is made by a vertical bore or passage 94 coaxial with, but of less diameter than, the bore 82. Also communicating with this bore 94 is a horizontal passage 96, which is connected by a pipe to a filter device 98 that, in turn, is connected with a compressed air supply pipe 100. Normally urging the valve head against its seat is a compression spring 102 located within the bottom of the bore 94 and pressing a valve-closing plunger 106 upwardly against the bottom of the valve head 86. The upper end of this plunger 106 is preferably of reduced diameter to permit the free passage of air through the portion of the bore 94 that communicates with the passage 96.

In order to compel both hands of the machine operator to be occupied and away from the dies at the time the air enters the press, two separate actuating handles are provided on opposite sides of the press frame and are coaxially pivoted on a horizontal rod or axle 112 passing through a bearing hole in the column 14 of the press frame. The handles 108, 110 have a non-rigid connection with the operating mechanism for the valve stem 84 in order to open the valve with a sudden or snap action rather than slowly, as will be more fully apparent from the following description of the details of such mechanism.

A transverse bridge or bar member 116 extends horizontally over the arm 16 of the frame in position to receive within a central socket 117 there-in the upwardly extending end of the valve stem 84. In order to actuate the bridge in a downward direction, a pair of substantially parallel tension rods 118, 120 are connected with opposite ends of the bridge at their upper ends by swivel connections. The position of the bridge on the rods may be adjusted by adjustment nuts 121 on the upper ends of the rods 118, 120. The lower ends of the rods 118, 120 are hooked into identical pivot lever arms 122, 124 on opposite sides of the frame and coaxially pivoted about the axle 112 of the operating handles. The arms 124 are connected with the handles 108, 110 by identical tension springs 126, so that as either one of the handles 108, 110 is depressed, its associated arm 124 will tend to follow it by reason of the spring connection. In order that the arm 124 may not immediately follow the movement of its actuating handle but shall await a predetermined movement of the handle, a pair of identical latch mem-

bers 128 of irregular, somewhat triangular shape (as indicated in Figs. 1, 7 and 8) are pivotally mounted on opposite ends of an axle rod 130 passing through the column 14 of the press frame. 5 Identical lugs 132 extend upwardly from the latch members 128 in position to engage identical shoulders 134 on the lower sides of the pivot arms 124. To normally hold the latch members 128 in such position, identical springs 136 urge 10 the latch members 128 into the position shown in Fig. 1. In order to disengage the lug 132 from shoulder 134 after the handles have descended a predetermined distance and put the arms 124 under tension, an anti-friction roller 138, mounted 15 upon the latch member 128 by a laterally extending pin 140, is engaged by the actuating handle when it has descended such predetermined distance. This position of engagement is shown in Fig. 7. Upon further depression of the handle 20 into the position of Fig. 8, it will be observed that the latch member 128 is caused to rotate about its pivot 130 and carry the lug 132 out of engagement with the shoulder 134. Since the depression of the handle has caused the spring 126 to be stressed, the disengagement of the lug and shoulder will cause the pivoted arm 124 to move in the direction that the operating handle has moved with a sudden or snap action, which will cause a similar sudden or snap action downwardly of 25 the tension rods 118, 120 (provided both handles are moved downwardly at once) and such downward movement will cause the bridge bar 116 to move the valve stem 84 downwardly to suddenly open the inlet valve.

In order that the movement of one handle shall not cause opening of the inlet valve, the movement permitted the arms 124, 108 and 110 is limited by identical stop pins 133 fixed in the side faces of the frame. The stop pins are so placed 30 that tilting of the bridge bar 116 effected by the depression of one handle, alone, will not open the inlet valve. To accomplish this purpose, the adjustment of the position of the bridge bar 116 upon the tension rods 118, 120 may be made so that 35 (when either one side or the other of the bar is tilted downwardly) the bar will only engage (but not move) inlet valve stem 84. With such adjustment, it will be obvious that upon depression of the other handle to cause both ends of the 40 transverse bar to be down simultaneously, the stem of the inlet valve will be depressed to open and admit compressed air to operate the plunger 45 50.

The same structure, adjusted by manipulation 55 of the nuts 121 so that the nuts are tight against the bridge bar 116 would cause opening of the inlet valve 86 with the same sudden snap action previously described when only one of the levers 108 or 110 was depressed sufficiently to trip the 60 latch member 128.

In order to return the actuating handles to their original position when the hands of the operator are removed, identical tension springs 65 144 are attached at one end to the mid-portion of the operating handles and at their other ends to anchor pins 146 laterally extending from the sides of the machine frame.

In order to permit exhausting of air from above 70 the piston 20 as it rises under the influence of the spring 32, an exhaust valve is provided in a passage branching from the passage 72. This passage comprises a three-stepped hole bored vertically upward through the bottom of the over-hanging arm 16 of the frame. The bottom or 75 largest portion of the hole receives a hollow plug

member 150 which is threaded into and secured within said largest portion. A cylindrical valve stem 152 is slidable within an axial passageway in the plug; and the upper end of the valve stem has an enlarged beveled head 154 adapted to seat upon a beveled seat 156 in the upper end of the plug member 150. A compression spring 158 presses upon the top of the head 154 to urge the head against its seat 156. The upper end of the spring 158 is received within a hollow screw bolt 160 that is screwed downwardly into a threaded hole directly above the head of the valve and on the opposite side of the passage 12. Between the stem and the head of the valve is a reduced neck; and there are radial passages 151 (Fig. 2) drilled through the plug 150 adjacent the valve neck to communicate with a circumferential groove 153 which, in turn, communicates with a horizontal boring 155 (Fig. 4) to the outside of the arm 16 of the press frame, a pipe 164 being connected with the outside end of this boring and leading down to a passageway 214 in the base 12 of the frame for directing and utilizing the exhaust air in a manner as will presently appear.

In order to hold the exhaust valve normally open but to cause it to close before the inlet valve opens, a transverse rod 166 has reduced end portions loosely fitting within holes in the actuating handles 108, 110 in such position as to cause the transverse rod 166 to engage the exhaust valve stem 152 and to raise the valve from its seat whenever the actuating handles are both raised. By reason of the loose connection of the transverse rod 166 with the actuating handles, depression of one handle will cause the rod to tilt and will permit the closing spring 158 of the exhaust valve to close the valve. Thus, depression of one or the other, or both, of the actuating handles will cause the exhaust valves to close but to open the inlet valve both handles must be simultaneously depressed. In this way the exhaust valve will always be closed before the inlet valve opens and the inlet valve will always close before the exhaust valve is opened.

In stamping operations, much time can be saved if the operator is not required to remove the stamped part from the die at the completion of the stamping operation. In order to automatically remove the stamped part, the present invention provides means for lifting the stamping from the cavity in the lower die and for blowing the stamped part off the die, all by utilization of the air that is exhausted when the piston 20 rises after the completion of the stamping operation.

A die block 200 is bolted upon the base 12 of the press frame. In order to raise the stamped part from the block, a plurality of vertically movable pins 202 are provided which may slide within passageways provided therefor in the die block or bottom die element 204. The lower ends of these pins connect with and move downwardly with a circular disk member 206 which seats upon a free piston 208, which slides within a passage 210 bored down into the upper surface of the base 12 of the press frame.

In order that air may have free access to the bottom of the piston 208, this piston is provided with a short stub stem 212 extending from its bottom face. For the purpose of delivering exhaust air to the bottom of the lower piston from above the upper or main piston 20, there is provided a passageway from the side face of the base of the press frame leading horizontally into the bottom of the bore 210 and this passage 214 is

connected at its outer end with the pipe 164, which, it will be recalled, connects with the passage leading to the exhaust valve.

For the purpose of directing exhaust air on the stamped blank or stamped part, a hollow dowel pin is received in a vertical bore passing through the die block 200 and through the base 12 into the air passage 214. At the top, the dowel pin presents a horizontally directed opening, so that air issuing therefrom will be directed against the stamped parts at an angle, preferably, so as to blow them away from the die at the conclusion of the stamping operation.

From the foregoing, it may now be observed that when the actuating handles are released, the inlet valve closes and the exhaust valve is opened, so that as the main piston 20 rises under the influence of the spring 32, the exhaust air above the piston head will be forced through the passages 10 and 12, and exhaust air passage 155 into the pipe 164 and through the passage 214 to a point beneath the small lower piston 208 which will thereupon be forced upwardly, pushing the pins 202 upwardly and causing the stamped part to rise from the die 204. Simultaneously, a portion of this exhaust air will pass through the hollow dowel pin 220 and issuing at the top, will blow the stamped parts away from the die.

After the air has become exhausted, the part raising piston 208 and the rods 202 associated therewith return to their original position. The return to the original position is accomplished by gravity acting on the parts, assisted by small springs coiled about the shanks of the pins 202 and pressing downwardly upon the disk 206, which is at the bottom end of these pins.

From the foregoing, it will be observed that the invention requires the operator to utilize both hands to operate the press, thus making it impossible for the operator to accidentally operate the press while his hands are in the path of the die.

One of the valuable features of the invention is that it provides mechanism for opening the inlet valve with a quick or snap motion so that the full impact of the live air will at once act on the piston which operates the upper die. That causes the piston to move the upper die with a hammer-like blow against the lower die. The invention also provides for the use of a minimum amount of live air, since it is only used for operating the press in one direction. The invention, nevertheless, provides for blowing off or away the stamped part by the utilization of the exhausted air to not only raise the stamped part from the lower die but also blow it away into a conveniently placed receptacle. It will be noted that the energy which is overcome by the live air in operating the upper die piston against its biasing spring is utilized with telling effect on the upward movement of the piston for forcing the exhaust air into useful channels.

In some uses of the invention, the press secures several parts by riveting or otherwise. Such assemblies are sometimes too heavy to be blown off the lower die. Nevertheless, the invention is useful in such cases without the blow-off, the assembly being taken off the die by hand or pushed off after it has been elevated or ejected from the die by the means hereinbefore described.

In cases where dual hand control is not deemed important or is not desired, as may sometimes be the case, the means for the sudden opening of the inlet valve may still be utilized together (if desired) with the utilization of exhaust air to

accomplish ejection of the stamped part from the die.

Thus although my invention possesses novel features all of which cooperate functionally to produce desired results, they are nevertheless individually valuable; and all or only some features may be used as occasion requires.

Many modifications within the scope of the invention will occur to those skilled in the art. Therefore I do not limit the invention to the specific embodiments described and illustrated.

I claim:

1. In an air-operated press, an air-operated piston, cooperating dies one of which is moved by said piston, inlet and exhaust valves controlling flow of air to and from said piston, cooperating means operating in coordination with the return stroke of said piston utilizing air exhausted by said return stroke to elevate a stamped article from the bottom die and to direct an air blast against said article to remove it from the die.

2. In a press, an air-operated piston, cooperating dies one of which is moved by said piston, inlet and exhaust air passages, valve means controlling the flow of air through said passages to and from said piston, means to cause closing of said exhaust passage prior to opening said inlet passage and vice versa, means for removing a stamping from said dies utilizing air exhausted by the return stroke of said piston, said removing means comprising a pneumatically-operated element for moving the stamping relative to the die, and means for directing a blast of exhausted air against the moved stamping to remove it from the die.

3. In an air-operated press, a pair of manual actuating handles, an air-operated piston, cooperating dies one of which is moved by said piston, inlet and exhaust valves operable by said handles controlling the flow of air to and from said piston, and means associated with said handles and said inlet valve for causing sudden opening of said valve, said opening means becoming effective only upon concomitant operation of both handles, and means associated with said handles for causing movement of said exhaust valve to closed position on actuation of either handle.

4. In an air-operated press, a pair of manual actuating handles, an air-operated piston, cooperating dies one of which is moved by said piston, 50 inlet and exhaust valves operable by said handles controlling the flow of air to and from said piston, means associated with said handles and said inlet valve for causing sudden opening of said valve, said opening means becoming effective only upon concomitant operation of both handles, and means associated with said handles for causing movement of said exhaust valve to closed position on actuation of either handle and requiring release of both handles before said exhaust valve 55 may open.

5. In an air-operated press, a pair of manual

actuating handles, an air-operated piston, cooperating dies one of which is moved by said piston, inlet and exhaust valves operable by said handles controlling the flow of air to and from said piston, and means associated with said handles and said inlet valve for causing sudden opening of said valve, said opening means comprising means acting on said inlet valve, means placed under stress by movement of said handles, and latching means restraining said means-acting-on-said-valve from opening said valve until both handles are operated.

6. In an air-operated press, a pair of manual actuating handles, an air-operated piston, inlet and exhaust valves controlling the flow of air to and from said piston, mechanism for operating said valves on actuation of said handles comprising dual latched members, dual latching members and means acting to open said inlet valve only when both latched members are released.

7. In an air-operated press, a pair of manual actuating handles, an air-operated piston, inlet and exhaust valves, controlling the flow of air to and from said piston, mechanism for operating said valves on actuation of said handles comprising a latched member and at latching member associated with each handle, means controlled by said members and acting to open said inlet valve only when both latched members are released.
